UNITED STATES PATENT OFFICE.

FRED W. TEMPLE OF CHICAGO, ILLINOIS, ASSIGNOR TO TEMPLE, INC., OF CHICAGO, ILLINOIS, A CORPORATION OF ILLINOIS.

DESIGN FOR A LOUD-SPEAKER.

Application filed October 12, 1927. Serial No. 23,732. Term of patent 14 years.

To all whom it may concern:

Be it known that I, FRED W. TEMPLE, a citizen of the United States, residing at Chicago, in the county of Cook and State of Illinois, have invented a new, original, and ornamental Design for a Loud-Speaker, of which the following is a specification, reference being had to the accompanying drawing, forming a part thereof.

Fig. 1 is a front elevation of a loud speaker showing my new design; and

Fig. 2 is a side elevation of the loud speaker.

I claim:

The ornamental design for a loud speaker, as shown.

FRED W. TEMPLE.
